UNITED STATES PATENT OFFICE.

MICHAEL I. SEILER, OF MILLERSBURG, PENNSYLVANIA.

EXPANSIBLE REAMER.

Application filed March 5, 1925. Serial No. 13,396.

This invention relates to expansible reamers.

The object is to provide a tool of this class, equipped with the usual spirally-arranged cutting elements, which are produced entirely by machining processes in order to secure the great degree of accuracy necessary to obtain the best results in fine work; such tools being ordinarily formed by a heating and twisting process which can not be relied upon for the desired accuracy.

Another object is to provide a reamer having such spiral elements formed on expansible sections integrally joined together to give the greatest strength and rigidity, said sections being readily expanded by a simple operation and adapted to automatically resume their normal relation to each other when desired, the expansion having no effect on the cutting elements except to render the device capable of reaming a larger hole or bore.

In carrying out these objects, I provide an expansible reamer having a plurality of radially-extending, spirally-formed cutting flutes or flanges, suitably bevelled or "backed off" to provide the necessary edge, and each flute having its forward end tapered to provide a first or initial point of attack on the metal to be removed in the reaming process, and also having a second point of metal attack at or near the center, which has the greatest diameter when the reamer is expanded.

A full and complete understanding of the invention may be obtained from a consideration of the following detailed description, taken in connection with the accompanying drawing forming a part of this specification; it being understood that while the drawing shows a practical form of the invention, the latter is not to be confined to strict conformity with the showing thereof, but may be changed or modified, so long as such changes or modifications mark no material departure from the salient features of the invention as specifically pointed out in the appended claims.

In the drawing, in which similar reference characters designate corresponding parts throughout the several figures:

Figure 1 is a side elevation of a reamer constructed in accordance with the invention.

Figure 2 is a longitudinal sectional view 55 of the same.

Figure 3 is a transverse sectional view thereof, and

Figure 4 is a detail section taken longitudinally of one of the spiral cutting flutes. 60

The improved reamer is formed of a single piece of suitable bar metal, preferably the best grade of tool steel, the same being round in cross section and of a diameter suitable to the size of the reamer to be produced. At one end, constituting the shank end 1 of the reamer, said bar is formed into a rectangular portion 2 for securing the tool in a turning head in the usual manner.

In proper spaced relation to the squared end of the shank, the bar is reduced by turning a circumferential channel 3 therein, and adjacent to the opposite end thereof, a similar channel 4 is formed, that portion of the bar beyond the latter channel constituting a head 5, and the portion between the channels 3 and 4 constituting the body of the reamer, somewhat larger in diameter than the head 5.

The body of the reamer is first provided with a bore or passageway 6 extending in from the head end thereof and on the longitudinal axis of the same to a point substantially midway between the aforesaid channels 3 and 4, or the center of the body. 75 The said bore here communicates with a smaller bore 7 which extends into the shank 1 of the reamer, the two bores being joined together by a tapered shoulder 8.

The inner shoulders 9 and 10 of the channels 3 and 4 respectively, are preferably bevelled back towards the center of the body as shown, and between these two points a series of spiral flutes 11 are formed by suitably machining the bar while the latter is given the proper amount of twist to carry the cutting tool substantially half way around the body of the tool, the outer active or cutting edge of the flutes being of the normal diameter of the bar.

In a right-hand reamer (as shown in the drawing) the spiral flutes 11 start at the inner channel 3 and extend half way round the body from right to left, and where a left hand reamer is to be made, the flutes extend in the opposite direction. The elongated cuts or grooves made to form the flutes have one wall extending substantially per-

pendicular to the axis of the reamer, while the other wall is formed on a curve extending out to the adjacent edge of the next flute, said cuts or grooves extending into the channels 3 and 4.

The peripheral edge of each flute is bevelled or "backed off" in a manner to form a cutting edge 12 at the perpendicular wall, or that wall of the flute which is directed toward the head end 5 of the reamer so that, as the reamer is turned to the right, said edge 12 will perform its function of entering and removing the metal from the hole or bore being reamed, and at each end the flutes are tapered inwardly, as shown at 13, the front tapers serving to cause the tool to enter the work and constituting the first point of metal attack.

As thus far described the structure constitutes a non-expansile spiral reamer suitable for use in many cases, and in order to have the added advantage of expansibility the body of the reamer is provided with a plurality of radially-disposed slits 14, extending from the central bores 6 and 7 to the outer face of the reamer, and intersecting the several flutes at an angle as a consequence of the spiral form of the flutes. The slits 14 are formed perfectly straight and exactly radial to the longitudinal axis of the reamer, and the same are very narrow so as not to form any material interruption to the continuity of the flutes. The slits form a series of sections in the body of the reamer which are adapted to be centrally expanded by means to be described.

The peripheries of the cutting flutes are now planed or ground off where traversed by the slits to provide flat surfaces 15 thereon, said surfaces being exactly perpendicular to the radial slits and extending equal distances at either side of the same. The surfaces 15 of the flutes along any one of the slits are all on the same plane, and form, in effect, tapered ends to each section of each flute on each expandable section of the reamer, in much the same manner as the tapered ends 13 at the terminals of the flutes, and as the reamer is turned these flat portions 15 will constitute a second point of metal attack for cutting into and removing the metal in the process of reaming.

When the reamer is expanded for use in a larger bore or hole, or when a larger amount of metal is to be removed, the greatest diameter is located midway between the channels 3 and 4 as the sections of the reamer, as defined between the slits, are forced radially outward from the axis thereof, and it will be seen that the tapered ends 13 at the front or head end of the reamer, together with the flat portions 15 located between the front end 13 and the center, will be forced to do the work of attacking the metal, as the reamer is forced through while turning to the right,

the following flat surfaces 15 being of gradually reducing diameter.

A steel pin 16 round in cross section and of a diameter to freely slide into the outer, larger bore 6 is fitted into the same, and is provided with a tapered inner end 17 to engage the aforesaid tapered shoulder 8, through the medium of which, when the pin is advanced into the bore, the sections comprising the body of the reamer are forced radially outward in an obvious manner.

The outer end portion of the pin is provided with screw threads 18, which engage the internal threads 19 of the bore 6, and the outer terminal of the pin is flattened as at 20 to facilitate turning the same to advance into the bore and expand the reamer.

It has been found in practice that the best results are obtained by forming eight equally spaced flutes half way round the body of the reamer, and to intersect the same by forming three slits, such arrangement providing a staggered relation between the several flat surfaces 15 on the different flutes and causing a more constant attack on the metal, and a more uniform pull or feed on the reamer, with a less expenditure of force or labor. A different number of flutes and slits may, however, be employed.

From the foregoing it will be seen that a machine made tool of great accuracy has been provided, which may be used for expediting the process of reaming bores, etc., said tool having a plurality of reaming flutes, each of which is provided with a plurality of points for attacking the metal or starting the cut, such points being in spaced and staggered relation to each other to cause the tool to advance more rapidly and to remove the metal more effectively, either when expanded or when in normal contracted condition.

What is claimed is:

1. An expandable reamer comprising a body round in cross section and having a bore extending from one end to near the other end thereof, a series of outstanding equally spaced flutes formed on the exterior of the body, said flutes extending throughout the length of the body and arranged spirally thereon to extend substantially half way round the same, the forward edge of each flute being formed into a cutting edge for reaming a bore, said flutes at their front ends being bevelled to form a first point of metal-attack, said body being divided into a plurality of integrally connected elongated, radially expandable sections by straight, radially-disposed longitudinal slits extending throughout the length of the body and intersecting a plurality of the flutes.

2. An expandable reamer comprising a round body member having a longitudinal bore and provided with exterior, spirally arranged ribs or flutes, each flute being bev-

elled to provide a forward cutting edge, the front end of each flute being tapered to form a first point of metal-attack, said body being divided into expandible sections by equally-spaced, radially-disposed, longitudinal slits, extending into the central longitudinal bore, said sections being integrally joined together at their ends, each slit intersecting a plurality of the ribs at an angle thereto, each section having its several flute portions tapered at the ends to form additional points of metal-attack.

3. An expandible reamer comprising a round body member having a longitudinal bore and provided with exterior, spirally-arranged ribs or flutes, each flute being bevelled to provide a forward cutting edge, the front end of each flute being tapered to form a first point of metal-attack, said body being divided into expandible sections by equally-spaced, radially disposed, longitudinal slits, extending into the central longitudinal bore, said sections being integrally joined together at their ends, each slit intersecting a plurality of the ribs at an angle thereto, each section of each flute, as defined by the slits, being inwardly tapered to said slits to constitute additional metal-attacking points.

4. An expandible reamer comprising an elongated body member having an internal bore, said body having a plurality of straight, longitudinal slits to provide outwardly expandible sections integrally joined together at their ends, a plurality of spirally-arranged cutting flutes formed exteriorly on the body member, said flutes being intersected by said slits, and each flute being tapered at its front end to provide a first metal-attacking point and also tapered at each intersection to provide additional metal-attacking points.

5. An expandible reamer comprising a round body member having a longitudinal bore and provided with exterior, spirally-arranged ribs or flutes, each flute being bevelled to provide a forward cutting edge, the front end of each flute being tapered to form a first point of metal-attack, said body being divided into expandible sections by equally-spaced radially-disposed, longitudinal slits, extending in to the central, longitudinal bore, said sections being integrally joined together at their ends, each slit intersecting a plurality of the ribs at an angle thereto, the flutes being provided in their peripheries with flat portions arranged perpendicular to the slits and extending an equal distance on either side of the same to provide second points of metal-attack on each flute.

6. An expandible reamer comprising an elongated body having a plurality of outstanding, spirally-arranged cutting flutes, each flute having a metal-attacking point at the front end, and a second metal-attacking point intermediate of its ends, said body being longitudinally slotted to provide expandible sections integrally-connected together at each end, said slits intersecting the flutes, and means for expanding the sections to cause the second metal-attacking points to function.

In testimony, that I claim the foregoing as my own, I have hereto affixed my signature.

MICHAEL I. SEILER.
